UNITED STATES PATENT OFFICE.

FREDERICK H. DECHANT, OF READING, AND WILLIAM R. ROHRBACH, OF SUNBURY,
PENNSYLVANIA.

GATE-VALVE.

1,171,841.

Specification of Letters Patent. Patented Feb. 15, 1916.

Application filed November 28, 1914. Serial No. 874,381.

To all whom it may concern:

Be it known that we, FREDERICK H. DECHANT and WILLIAM R. ROHRBACH, both citizens of the United States, respectively 5 residing at Reading and Sunbury, in the counties of Berks and Northumberland and State of Pennsylvania, have invented certain new and useful Improvements in Gate-Valves, of which the following is a specification.

Our invention relates particularly to stop valves in which the liquid passage-way is closed by the lowering of a gate valve.

In order that the valve may be properly seated around the flow passage opening it is necessary to extend the valve chamber below the bed of the flow passage so as to permit proper descent of the valve; but the depression or pocket thus formed tends to collect heavy matter carried by the flowing liquid so as to nevertheless prevent proper lowering of the valve.

Our invention consists in providing in the chamber a movable false-bottom which is positively operated by the valve so that when the latter is opened the false-bottom will be positioned in approximate alinement with the passage-way and prevent access of sludge, stones, or like material to the depressed pocket, while the lowering of the valve will automatically displace the false-bottom so as to surely permit its proper seating.

The invention is fully described in connection with the accompanying drawings illustrating a preferred embodiment thereof, and the novel features are particularly pointed out in the claims.

Figure 1 is a longitudinal section showing only one half of a valve casing and the parts therein, with the latter represented in raised position; and Fig. 2 is a similar view showing the parts in lowered position; the duplicate valve disks, shown in the two figures 45 being jointly operated. Fig. 3 is a half cross-section corresponding with Fig. 1; Fig. 4 is a similar section corresponding with Fig. 2; and Figs. 5 and 6 are corresponding sectional plan views on the lines 50 5-5 and 6-6 respectively of Fig. 3.

The casing 2 as shown is formed as usual with a valve chamber 3 having seated apertures 4, 4 communicating with alined flow passage-ways 5, 5; the gate valve in said

chamber comprising duplicate valve disks 55 6, 6 which are jointly engaged by a nut 7 on an operating screw 8 suitably mounted in the casing cap. The chamber 3 has a downward extension 3^a forming a pocket below the bottom or bed of the flow passage, into 60 which the valve is lowered in the closing operation sufficiently to permit of properly seating the disks around the apertures 4, 4. Any suitable wedging means, not shown, may be employed for pressing the lowered 65 disks against their seats as usual.

To provide for normally cutting off the lower chamber extension 3^a, so as to prevent the collection of obstructing matter therein and at the same time present an unbroken bed for the liquid flowing through the casing, I employ a pair of false-bottom shutters 10, 10^a, suitably mounted within the valve chamber 3 of the casing so as to be positively swung into either open or closed 70 position, by the lowering or raising of the valve. These shutters, as shown, are suitably pivoted within the casing, at points 11, 11^a on opposite sides and preferably in the horizontal axial plane of the flow passage-way, so that the curved lower portions thereof may be swung together to form a closed bottom in line with the bed of the passage-way as indicated in Figs. 1 and 3, or swung 75 apart so as to open the chamber extension 85 3^a for descent of the valve as indicated in Figs. 2 and 4. Each shutter is provided, as shown, with an upper valve-engaging portion 12, above its pivot point; so that the reciprocating valve will contact with these 80 portions to positively swing the shutters to closed position in the act of opening the valve, while the closing of the latter freely swings them to open position as indicated in Figs. 2 and 4. The opposing inner faces of 90 these upper portions 12, 12 of the shutters, are provided with ribs 14, forming guide ways adapted to retain the valve disks 6, 6 in proper relation during their reciprocating movement.

It will be readily seen that both the opening and closing movements of the valve automatically and positively operate the shutters, so as to advantageously cut off the chamber extension 3^a when the valve is open 95 105 while at the same time permitting its free closure.

The specific construction set forth may

obviously be modified without departing from the invention.

What we claim is:

- 5 1. A stop valve having a casing with a valve chamber and a communicating flow passage-way, a gate valve, means for reversely moving the latter to open or close said passage-way, and a false-bottom shutter pivotally mounted in said chamber and arranged to be positively swung by operation of the valve.
- 10 2. A stop valve having a casing with a valve chamber and a communicating flow passage-way, a gate valve, means for reversely moving the latter to open or close said passage-way, and a pair of false-bottom shutters pivotally mounted in said chamber and arranged to be positively swung in reverse directions by operation of the valve.
- 15 3. A stop valve having a casing with a valve chamber and a communicating flow passage-way, a gate valve, means for reversely moving the latter to open or close said passage-way, and a pair of false-bottom shutters pivotally mounted in said chamber and provided with valve-engaging portions whereby they are positively swung
- 20 25

in reverse directions by operation of the valve.

4. A stop valve having a casing with a valve chamber and a communicating flow passage-way a gate valve, means for raising and lowering the latter to open or close said passage-way, and a pair of false-bottom shutters separately pivoted within said chamber and provided with upward extensions operatively engageable by the reciprocating valve.

5. A stop valve having a casing with a valve chamber and a communicating flow passage-way, a gate valve, means for raising and lowering the latter to open or close said passage-way, and a pair of valve-operated false-bottom shutters separately pivoted within said chamber and provided with upward extensions having guide ways for the reciprocating valves.

In testimony whereof we affix our signatures in presence of two witnesses.

FREDERICK H. DECHANT.
WILLIAM R. ROHRBACH.
